UNITED STATES PATENT OFFICE.

ALFRED ST. JAMES, OF BROOKLYN, NEW YORK.

SPARK-PLUG.

1,258,269.

Specification of Letters Patent.

Patented Mar. 5, 1918.

Application filed October 9, 1916. Serial No. 124,578.

To all whom it may concern:

Be it known that I, ALFRED ST. JAMES, a citizen of the United States, residing at Brooklyn, in the county of Kings, State of New York, have invented certain new and useful Improvements in Spark-Plugs; and I do hereby declare the following to be a full, clear, and exact description of the invention, such as will enable others skilled in the art to which it appertains to make and use the same.

This invention relates to spark plugs.

The object of the invention is to provide a spark plug of such character that it will be more positive and certain in operation than those plugs which are known to me, and that it is provided with an improved form of electrodes whose coöperation is less likely to be affected by carbon deposits or changes in adjustment.

A further object of the invention is to construct a spark plug in which the electrodes are readily removable, and are furthermore accessible for the purposes of renewal without requiring the demounting of the entire plug. Both of the electrodes are of such construction that they may be very cheaply produced so that their renewal in the plug body is a source of very inconsiderable expense, and since the plug body is used as a permanent structure, the cost of up-keep of spark plugs, when pursued according to the methods permitted by my improved construction need be very small.

With the above objects in view and such other objects as may hereinafter appear, my invention will now be fully set forth and described, reference being had to the accompanying drawings.

40 In the drawings:—

Figure 1 is a longitudinal elevation of the spark plug,

Fig. 2 is a longitudinal section thereof,

Fig. 3 is an end view,

45 Fig. 4 is a view of a blank used in the manufacture of one of the terminals, and

Fig. 5 is a detailed elevation of the other terminal.

Referring to the drawing, there is shown 50 a metallic casing 1 which is exteriorly threaded in the usual manner to engage the corresponding opening leading to the exploding chamber of an explosive engine cylinder. The casing 1 is formed exteriorly 55 angular in its upper portion as shown at 2 to receive a wrench, as usual, and incloses a

chamber 3. In the construction illustrated, the end wall of the casing opposite to the closed portion is flat and is provided with threaded recesses. Against this flat end wall 60 is disposed the ground terminal of the plug consisting of a disk 6 which is slotted radially at its central portion and dished with resultant sparking points 7 in mutual spaced relation and touching a common plane. The 65 marginal portion 5 of the disk is provided with perforations 8 through which are engaged screws that take into the threaded recesses in the end wall of the plug casing and serve to hold the disk removable to the 70 casing. Within the chamber 3 is mounted the opposite terminal 10 which, as best seen in Fig. 5 is an elongated stem which terminates at its lower end in a conical base 11 and a screw threaded foot 12. The latter is 75 adapted to be received in a head 13 which is seated upon the bottom of the chamber 3 within the plug 1 and forms the upper end of a rod or step 14, which extends through the bottom of the casing 1, and is surrounded 80 by a suitable insulating sleeve 15. The stem 14 is also insulated from the casing 1 and the wall 2 by means of the insulating disk 16 and the collar 17. The stem 14 serves to hold the parts in assembled relation, a lock 85 nut 18 threaded upon the upper end of the stem 14 bearing against the insulator 15 and locking the several parts together, it being remembered that the head 13 bears upon the bottom of the chamber 3. The binding 90 screw 19 above the lock end 18 provides a suitable means for connecting a lead wire to the plug.

From the foregoing, it is obvious that it is a very simple matter to renew the terminal 5, and that since the latter is formed of a plurality of independent free points it is a comparatively simple matter to adjust the points with relation to the electrode 10 so that a certain operation of the plug is assured. Furthermore, the terminal 10 is as easily renewed without disturbing the assemblage of the stem 14 or the remaining parts of the plug other than to remove the terminal 5. The device is simple and inexpensive in manufacture, and may be used indefinitely as a complete device merely by the renewal of one of the terminals at infrequent intervals as the occasion may require.

110 What I claim as my invention is:—

1. A removable terminal for spark plugs

consisting of a disk having perforations in its marginal portion to receive attaching means and having its central portion radially slotted and dished with resultant sparking points in mutual spaced relation and touching a common plane at right angles to the axis of the disk.

2. A spark plug comprising a casing adapted for engagement with the cylinder
10 of an explosive engine, a ground terminal including a disk having its marginal portion removably connected with the casing

and having its central portion radially slit-
ted and dished with resultant sparking
points in mutual spaced relation and a sec- 15
ond terminal carried by and insulated from
the casing in sparking relation to said
points.

In testimony whereof, I affix my signature, in the presence of two witnesses.

ALFRED ST. JAMES.
